VARIABLE RESISTANCE PHONOGRAPH
PICKUP AND SYSTEM

Walter L. Eckhardt and Madison Cawein, Fort Wayne, Ind., assignors, by mesne assignments, to Farnsworth Research Corporation, a corporation of Indiana

Application July 5, 1945, Serial No. 603,362

16 Claims. (Cl. 179—100.4)

1

This invention relates generally to phonograph pickup devices and more particularly to a phonograph pickup device adapted to translate sound recordings of the hill and dale type and also of the lateral cut type.

Conventional phonograph pickup devices usually comprise a stylus and an electromagnetic device or a stylus and a crystal. Both of these forms of pickup devices unavoidably have a comparatively high mass and they possess certain characteristics which make them resonant in a portion of the audio frequency band. To provide such devices having a relatively uniform frequency response over the entire audible frequency range entails numerous design problems.

The relatively high mass of such devices causes them to have a sluggish response in the higher frequencies of the audible range and prevents instantaneous response of the stylus to the higher frequency vibrations which are cut in a record. This results in a relative change of phase between the low frequency sound signals and the high frequency sound signals so that the high frequencies have a time delay with respect to the low frequencies. Thus the sound which is reproduced does not have the same phase relationship between the high and low frequency components as compared to the phase relationships which were established on the record.

The characteristics of conventional pickup devices such as those enumerated in the foregoing discussion make it particularly difficult to provide a pickup device which is capable of responding to sound recordings of both the hill and dale type and the lateral cut type. Ordinarily a pickup device which responds to both types of recordings must necessarily have a relatively higher mass than a pickup which is designed to respond to a single type of recording. Thus the quality of response of a conventional pickup capable of responding to both types of recordings is even lower than that of a pickup which is specifically designed to respond to a single type of recording.

Accordingly, it is the principal object of this invention to provide a phonograph pickup device having a uniform response characteristic over substantially the entire audible frequency band and adapted to translate hill and dale recordings or lateral cut recordings.

A further object of this invention is to provide a phonograph pickup device, the mass of which is reduced with respect to that of conventional pickup devices.

A still further object of this invention is to

2

provide a phonograph pickup device of such mass as to preserve the phase relationship between recorded high and low frequency components of a sound signal.

Another object of this invention is to provide circuit means for cooperating with a pickup capable of translating recordings of the hill and dale type or of the lateral cut type whereby to control the electrical output of the device and selectively effect a response to one or the other types of recordings.

Still another object of this invention is to provide a circuit adapted to convert the pickup device from one which responds to hill and dale recordings to one which responds to lateral cut recordings, or vice-versa and at the same time prevent amplification of recordings of the non-selected type.

In accordance with this invention there is provided a phonograph pickup device consisting of a flexible means, means for flexing the flexible means and a plurality of resistance members disposed on the flexible means so as to be variable by vertical and horizontal flexing of the flexible means.

In accordance with a further feature of this invention, there is provided a phonograph pickup device adapted to reproduce records of the hill and dale type or of the lateral cut type. This device comprises a flexible means having a portion at one end adapted to be fixed to a phonograph pickup arm together with an extended portion having a stylus fixed at its free end for flexing the extended portion in response to hill and dale sound tracks or lateral cut sound tracks. There is provided on the extended portion of the flexible means an electrically resistive means for effecting control of an electric circuit when the extended portion is flexed in a vertical or horizontal plane.

For electrically controlling the output of the phonograph pickup device provided in accordance with this invention, there is provided an electrical circuit consisting of potential dividers connected across certain components of the electrically resistive means in the pickup device for rendering certain ones of said components effective for responding to hill and dale sound tracks and certain others of said components effective to respond to sound tracks of the lateral cut type.

For a better understanding of the invention, together with other and further objects thereof, reference is made to the following description, taken in connection with the accompanying

drawings, and its scope will be pointed out in the appended claims:

In the accompanying drawings:

Fig. 1 of the drawings is an elevation of the pickup device provided in accordance with this invention together with its associated pickup arm which is shown partially in cross section;

Fig. 2 is a plan bottom view of the device illustrated in Fig. 1;

Fig. 3 is an exploded perspective of the pickup device provided in accordance with this invention;

Fig. 4 is a cross section taken on line 4—4 of Fig. 3;

Fig. 5 is a fragmentary cross section of the pickup device taken on line 5—5 of Fig. 4;

Fig. 6 is a circuit diagram illustrating a control circuit provided in accordance with this invention and incorporating the electrically resistive means which form a portion of the pickup devices illustrated in Figs. 1-5;

Fig. 7 is a perspective view of a modified form of the pickup device illustrated in Fig. 3 with the stylus mounting omitted; and

Fig. 8 is a cross section taken on line 8—8 of Fig. 7.

Referring now to Figs. 1, 2 and 3 of the drawings, there is illustrated a preferred modification of this invention consisting of a pickup arm 1, a pair of clamping members 3 and 4 fixed to pickup arm 1 by suitable screws 6 and 7 together with sound translating pickup 10. Pickup device 10 includes an enlarged portion 11 which is adapted to be clamped between elements 3 and 4 by means of screws 12 and 13. Integrally formed with the enlarged portion 11 of pickup element 10 is an extended portion 15 to which is attached, in a manner to be described hereinafter, a stylus 16 for tracking the groove of a hill and dale type record or a lateral cut record.

Pickup element 10 may be formed of any type of insulating material such, for example, as plastics like Celluloid, polystyrene or other materials of similar flexibility and mass. On the extended portion 15 of pickup element 10 a number of grooves 18, preferably four, are cut which may be of the order of $\frac{1}{16}$ inch in depth whereby to provide vertical and horizontal surfaces on which may be painted or otherwise deposited layers of electrically resistive material 20, 21, 22 and 23 such, for example, as finely divided carbon particles similar to graphite. Thus, there is provided comparatively long strips of electrically resistive material. The strips cover the parts of the surface of portion 15 located in the quadrants between the vertical and horizontal axes of portion 15. When portion 15 is flexed, the contact pressure between the carbon particles changes thereby to change the electrical resistances of the strips.

The layers of resistive materials 20, 21, 22 and 23 are adapted to respond electrically to sound records of either the hill and dale type or of the lateral cut type. When the extended portion 15 is flexed in a vertical direction as in the case of hill and dale records, the carbon particles along the horizontal surfaces 25 of the strips 20, 21, 22 and 23 are, in effect, moved to vary the contact pressure between adjacent particles. For example, when portion 15 is flexed downwardly, the particles on the upper horizontal surfaces tend to separate whereas the particles on the lower horizontal surfaces tend to move closer to one another. On the other hand, when portion 15 is flexed upwardly the reverse is true.

Thus, the resistance changes in the upper and lower surfaces 25 are equal and opposite and the currents which flow through the resistive strips may be utilized to operate a push-pull amplifier device as will be described hereinafter.

When the extended portion 15 is vibrated in a horizontal plane as in the case of lateral cut records, the vertical surfaces 26 of the resistive strips are stressed in a manner similar to that described in connection with the horizontal surfaces 25. In a similar manner, there is produced equal and opposite changes of resistance which may also be utilized to operate a push-pull amplifier device.

In order to provide electrical contact with the resistive strips, they are continued from extended portion 15 onto the surfaces of enlarged portion 11. Thus, for example, resistive strip 20 is terminated on enlarged portion 11 by a conductive coating 28 and resistive strips 21, 22 and 23 are also terminated on enlarged portion 11 in conductive coatings 29, 30 and 31, respectively. Clamping member 3 includes fixed terminals 33 for engaging conductive coatings 29 and 31. Clamping member 4 includes as an adjustable clamping portion thereof a terminal strip 35 which is adjustably mounted on member 4 by setscrews 36. Member 35 includes terminals 38 affixed thereto for engaging with conductive coatings 29 and 31. When pickup device 10 is initially affixed to clamping members 3 and 4, it is placed so that the enlarged portion 11 protrudes between the clamping members with the conductive coatings 28, 29, 30 and 31 in juxtaposition with terminals 33 and 38. Setscrews 36 may then be rotated to move terminal strip 35 and contact members 38 into engagement with the conductive coatings to provide intimate electrical contact therewith. Terminals 33 and 38 may be connected to the exterior of clamping members 3 and 4 by conductors 40.

For supporting the stylus at the free end of extended portion 15, there is provided member 42 having a conductive coating 43 which may be clamped to extended portion 15 by means of screws 44, thereby to provide a support for stylus 16 and intimate electrical contact between all of the resistive strips 20, 21, 22 and 23. For providing an electrical connection to coating 43, there is a bore 47 (Figs. 4 and 5) within extended portion 15 through which extends conductor 48. At the free end of enlarged portion 11, there is provided a conductive pin 51 to which conductor 48 may be connected and to which may be connected conductive coatings 52 which are disposed on the outer surface of enlarged portion 11. Coatings 52 may be connected to the exterior of clamping members 3 and 4 by means of contacts 53 on the clamping members and conductors 54.

Referring to Fig. 6 of the drawings, there is illustrated a circuit adapted to control and amplify the electrical variations produced in conductive strips 20, 21, 22 and 23. These strips appear in Fig. 6 as resistors indicated by identical reference characters. The member 42 (Fig. 3) for joining the ends of the conductive strips, is indicated by the same reference character in Fig. 6. For providing a means for converting the pickup device from a hill and dale pickup to a lateral cut pickup, or vice versa, there are provided potentiometers 60, 61, 62 and 63 which are connected across resistors 21—20, 20—22, 22—23 and 23—21, respectively.

The slider 65 of potentiometer 60 and slider

66 of potentiometer 61 are connected to a point 68 common to resistor 20 and potentiometers 60 and 61. The point 68 is also connected through conductor 67 to the control grid of vacuum tube 70. Point 68 is also connected through resistor 5 72 to the positive side of the source of potential 74. The plate resistors 75 and 77 are also connected to the positive side of source 74 and to the plates of tubes 70 and 71. The sliders 79 and 80 of potentiometers 62 and 63, respectively, are connected to the point 81 common to resistor 23 and potentiometers 62 and 63. Point 81 is connected through conductor 82 to the control grid of vacuum tube 71. Point 81 is also connected through resistor 73 to the positive side of source 15 74.

Tubes 70 and 71 are connected to form a conventional push-pull amplifier circuit. As stated hereinbefore, the resistors 20 to 23 are varied in effective value to provide a push-pull variation of current. Therefore, the push-pull amplifier circuit is provided with a push-pull input. Across output terminals 84 and 85 there may be derived an amplified audio signal.

The circuit illustrated in Fig. 6 effectively provides either a volume control or a switching circuit for converting the pickup device 10 for operating in conjunction with hill and dale type record grooves or lateral cut record grooves. If it is desired to utilize the pick-up device in conjunction with hill and dale record grooves, potentiometer slider 65 is moved to the extreme left position to short-circuit resistor 60 while potentiometer slider 79 is simultaneously moved to its extreme right position to short-circuit resistor 62. Thus current flows from source 74 through resistor 72, through resistors 20 and 21 to ground and also from source 74 through resistors 13, 22 and 23 to ground. As the resistance of the resistors changes in response to the sound waves cut in the record, variable potentials are impressed on the grids of tubes 70 and 71. Potentiometers 61 and 63 may be varied to effect a volume control.

In the case of lateral cut records, potentiometer sliders 66 and 80 may be moved to their extreme lower and upper positions respectively to short-circuit respectively resistors 61 and 63. Thus the changes of resistance effected by lateral vibrations of the pickup device cause variable potentials on the grids of the tubes 70 and 71. For volume control, potentiometers 60 and 62 may be varied.

Referring to Figs. 7 and 8 of the drawings, there is illustrated a modification of the pick-up device 10. In this modification, the extended portion 15 is provided with rectangular channels 90, 91, 92 and 93 which are disposed on the vertical and horizontal axes of portion 15, as best illustrated in Fig. 8. The channels are filled with a resistance material as in the preferred modification to form resistive strips 20, 21, 22 and 23. These strips are continued to enlarged portion 11 to form terminal strips 28, 29, 30, 31 and 52, as in the preferred modification. The stylus-supporting device 42 may be secured to the free end of portion 15 in the same manner as illustrated in Fig. 3.

In this modification, flexure of portion 15 by a hill and dale record groove varies the resistance of strips 20 and 22 by equal and opposite amounts similarly to provide a push-pull electrical signal. A conventional push-pull amplifier may be utilized to amplify the signals and switches may be provided for connecting whichever strips are desired to be effective.

From the foregoing, it is evident that there is provided in accordance with this invention a phonograph pickup device having a substantially uniform frequency response characteristic and adapted to translate either hill and dale recordings or lateral cut recordings. The mass of this pickup device is such that its inertia effects do not prevent instantaneous response of the stylus, whereby all audible frequencies are reproduced faithfully with respect to their phase.

While the drawings illustrate the preferred features of this invention, it will be obvious to those skilled in the art that the inventive concept includes various modifications. For example, the pickup member 10 is illustrated as having channels for receiving resistance material but it is within the scope of this invention to coat the outer surface of the pickup member with strips of resistance material of a desired thickness whereby to provide a pickup device which will operate in the same manner as that illustrated in the drawings. It is also obvious that various other arrangements of contact strips may be provided on pickup device 10 such, for example, as foil or rigid metallic strips. Further, it is not necessary to utilize the particular type of clamping members shown in the drawings as any suitable mechanical arrangement falls within the scope of this invention.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. Sound translation apparatus comprising flexible means, means fixed thereto for flexing said flexible means, a plurality of channels disposed on said flexible means, certain of said channels comprising surfaces disposed at 90° angles to the surfaces of certain others of said channels and resistive material fixed to said surfaces.
2. Sound translation apparatus comprising flexible means, means fixed at one end thereof for flexing said flexible means, a plurality of channels diagonally disposed on the outer surface of said flexible means and strips of resistive material fixed to said surfaces.
3. Sound translation apparatus comprising flexible means, means fixed thereto for flexing said flexible means, a plurality of channels disposed on said flexible means, each channel comprising surfaces disposed at 90° angles to one another and strips of carbonaceous material fixed to said surfaces.
4. Sound translation apparatus comprising flexible means, means fixed at one end thereof for flexing said flexible means, a plurality of channels disposed on the outer surface of said flexible means, each channel comprising surfaces disposed at 90° angles to one another and strips of carbonaceous material fixed to said surfaces.
5. Sound translation apparatus comprising flexible means having a portion at one end adapted to be fixed to a phonograph pickup arm and an extended portion having four channels spaced from one another on diagonal lines with respect to the longitudinal axis of said means, a stylus fixed at the free end of said extended portion for flexing it in a vertical or horizontal plane and electrically resistive material fixed to

the surfaces of said extended portion which define said channels.

6. Sound translation apparatus comprising flexible means having a portion at one end adapted to be fixed to a phonograph pickup arm and a reduced portion having four channels spaced from one another and disposed in the four quadrants defined by the vertical and horizontal axes of said portion, a stylus fixed at the free end of said extended portion for flexing it in a vertical or horizontal plane and electrically resistive material fixed to the surfaces of said extended portion which define said channels.

7. Sound translation apparatus comprising flexible means having a base portion at one end adapted to be fixed to a phonograph pickup arm and an extended portion having four channels spaced from one another and disposed in the four quadrants defined by the vertical and horizontal axes of said portion, a stylus fixed at the free end of said extended portion for flexing it in a vertical or horizontal plane and carbonaceous particles fixed to the surfaces of said extended portion which define said channels.

8. Sound translation apparatus comprising flexible means having an enlarged portion at one end adapted to be fixed to a phonograph pickup arm and an extended portion having four channels spaced from one another and disposed in the four quadrants defined by the vertical and horizontal axes of said portion, electrically resistive means fixed to the surfaces of said extended portion which define said channels, conductive means secured to the free end of said extended portion in contact with said resistive means, terminal strips on the surface of said enlarged portion some of which are connected to said resistive means, a conductor extending from said conductive means through said extended portion into said enlarged portion and electrically connecting said conductive means to one of said terminal strips and a stylus fixed to said conductive means for flexing said extended portion in a vertical or horizontal plane.

9. Sound translation apparatus comprising flexible means having an enlarged portion at one end adapted to be fixed to a phonograph pickup arm and an extended portion having four channels spaced from one another and disposed in the four quadrants defined by the vertical and horizontal axes of said portion, carbonaceous strips fixed to the surfaces of said extended portion which define said channels, conductive means secured to the free end of said extended portion in contact with all of said carbonaceous strips, terminal strips on the surface of said enlarged portion some of which are connected to said carbonaceous strips, a conductor extending from said conductive means through said extended portion into said enlarged portion and electrically connecting said conductive means to one of said terminal strips and a stylus fixed to said conductive means for flexing said extended portion in a vertical or horizontal plane.

10. Sound translation apparatus comprising flexible means having a portion at one end adapted to be fixed to a phonograph pickup arm and an extended portion, said extended portion including vertically and horizontally disposed channels a stylus fixed at the free end of said extended portion for flexing it in a vertical or horizontal plane and electrically resistive elements fixed to the surfaces of said channels in alignment with the vertical and horizontal axes of said extended portion.

11. Sound translating apparatus comprising flexible means, means fixed thereto for flexing said flexible means, first resistance means disposed on said flexible means so as to be variable by vertical flexing of said flexible means, second resistance means disposed on said flexible means so as to be varied by horizontal flexing of said flexible means, amplifier means including an input circuit and voltage dividing means for coupling either said first resistance means or said second resistance means to said amplifier means.

12. A sound-translating circuit comprising electrical pickup means consisting of a plurality of resistors adapted to be varied in response to hill and dale or lateral cut recordings, means for shunting successive pair of resistors for controlling the response thereof, push-pull amplifier means including a pair of input circuits and conductor means for coupling said shunting means to said input circuits.

13. A sound-translating circuit comprising electrical pickup means consisting of a plurality of resistors adapted to be varied in response to hill and dale or lateral cut recordings, potentiometers connected across said resistors for controlling the response of said resistors, push-pull amplifier means including a pair of input circuits, conductor means for coupling the sliders of one pair of potentiometers to one of said input circuits, conductor means for coupling the sliders of another pair of potentiometers to the other of said input circuits and a source of potential connected between said amplifier and said potentiometers.

14. A sound-translating circuit comprising electrical pickup means consisting of a plurality of resistors adapted to be flexed in response to hill and dale or lateral cut recordings, means for connecting said resistors to a common point, potentiometers connected across the free ends of said resistors to form a star connection whereby successive pairs of resistors are shunted by said potentiometers for controlling the response of said resistors, amplifier means including a pair of vacuum tube input circuits, means for coupling the sliders of one pair of adjacent potentiometers to one of said input circuits, means for coupling the sliders of another pair of adjacent potentiometers to the other of said input circuits and a source of potential connected between said common point and points of said star connection between the potentiometers of each said pair.

15. A sound-translating circuit comprising electrical pickup means consisting of a plurality of resistors adapted to be flexed in response to hill and dale or lateral cut recordings, means for connecting one end of each resistor in common, potentiometers connected across the other ends of said resistors to form a star connection whereby successive pairs of resistors are shunted by said potentiometers for controlling the response of said resistors, push-pull amplifier means including a pair of input circuits, means for coupling the sliders of one pair of adjacent potentiometers to one of said input circuits, means for coupling the sliders of another pair of adjacent potentiometers to the other of said input circuits and a source of potential connected between said common connecting means and points of said star connection between the potentiometers of each said pair.

16. A sound-translating circuit comprising electrical pickup means consisting of a plurality

of resistors adapted to be flexed by vibration in first and second planes in response to the hill and dale or lateral cut recordings, means for connecting one end of each resistor to ground, potentiometers connected across the other ends of said resistors to form a star connection whereby successive pairs of resistors are shunted by said potentiometers for controlling the response of said resistors, push-pull amplifier means including a pair of input circuits, conductor means for coupling the sliders of one pair of adjacent potentiometers to one of said input circuits, conductor means for coupling the sliders of another pair of adjacent potentiometers to the other of said input circuits and a source of potential connected 15

between ground and points of said star connection between the potentiometers of each said pair.
